(57) CLAIM

The ornamental design for a case for an injection device, as shown and described.

DESCRIPTION

FIG. 1 is a top perspective view of a case for an injection device showing our new design, the top cover of the case in a closed position;

FIG. 2 is a front view of the case shown in FIG. 1;

FIG. 3 is a top view of the case shown in FIG. 1;

FIG. 4 is a bottom view of the case shown in FIG. 1;
FIG. 5 is a top perspective view of the case shown in FIG. 1 illustrating the top cover of the case pivoted to an open position, and an interior injection device holder of the case in a closed position;

FIG. 6 is a top perspective view of the case shown in FIG. 1 illustrating the top cover of the case pivoted to an open position, and an interior injection device holder of the case pivoted to an intermediate open position; and,

FIG. 7 is a top perspective view of the case shown in FIG. 1 illustrating the top cover of the case pivoted to an open position, and an interior injection device holder of the case pivoted to a fully open position.
